UNITED STATES PATENT OFFICE.

ANTON J. PLOTZ, OF CHICAGO, ILLINOIS.

GUARD FOR REELS.

Application filed July 6, 1925. Serial No. 41,587.

This invention relates to improvements in guards for reels such as used for flexible electrical conductors, cables, and the like, and has among its objects the provision of 5 a new and useful guard for reels which will act to prevent the entangling of the conductors or cables between the flanges of the reel and its support.

At the present time one or more reels are 10 mounted on a support similar to one as shown in the attached drawing and considerable time is lost in manufacturing plants employing such reels during winding of the cables or conductors back on the reels after 15 their use. A great number of these reels are employed or used at one time in making up switch boards and the like, and after the use of the desired length of each particular cable or conductor from the reel, the unused 20 withdrawn end must in each case be rewound on the reel. This rewinding is done by manually turning the reel and during this rewinding the unwound ends invariably 25 are not guided or feidred in a way to guide them properly onto the reels, and hence by engagement with the flange of the reel, the conductor is drawn into the small space between the reel flange and the reel supporting 30 frame. To overcome this inherent disadvantage in loss of time in rewinding cables onto their drum is an object of my invention.

Another object of my invention resides in 35 the provision of a guard of simple construction which renders the manufacture thereof at a comparatively low cost.

With these and other objects in view, my 40 invention consists in the novel combination, construction and arrangement of the parts and members shown in the accompanying drawing, described in the following specification, and particularly pointed out in the 45 appended claims.

In the illustrations, Figure 1, shows a side 50 elevation of a device for retaining cable reels embodying my invention and showing the lower reel with its support and guard in cross section. Figure 2, shows a front elevation of same with the upper reel in section.

Referring to the illustrations 10 indicates 55 a hanger or frame of bar material having a twisted upper portion forming an eye 10^a for support on the hook 11 and having its lower ends 10^b bent toward each other at

right angles for insertion within the tubular center 12^a of the reel 12.

The reels 12, shown in the illustrations, comprise a tubular center 12^a having integral flanged disk-like ends 12^b, the periphery of 60 which ends is provided with a groove 12^c.

The lower reel 12, as above stated is loosely supported directly on the bent ends 10^b while the upper is loosely mounted on a pair of extensions 10^c which are welded to 65 the hanger 10.

The cable guards which form the principal part of my invention comprise a metallic bar 13 of round cross section which is bent to form a pair of concentrically arranged segmental portions 13^a having an integral portion 13^b interconnecting same at their lower ends. A plurality of cross bars, 13^c, 13^d, and 13^e of like cross section are suitably spaced and welded to the tops of the two 75 segments 13^a. The cross bars 13^c, 13^d and 13^e being parallel with the portions 13^b.

By reference to the illustrations, it will be observed that the segments 13^a are spaced apart a distance equal to the distance between 80 the grooves 12^c of the reel flanges and that same are arranged to fit within said grooves 12^c.

For the purpose of retaining the segments 13^a against displacement, I provide, a flat 85 cross member 14 which is welded to the top of the two segments 13^a and which member 14 is provided with a pair of end openings 14^a through which the hanger 10 extends.

The cable or rope 15 which is wound on 90 the reel 12 is arranged to have the free end 15^a extend through the opening in the guard 13 located between the cross bar 13^e and the integral cross portion 13^b.

By reference to the illustrations, and 95 particularly to Figure 2, it will be observed that as the flange 12^b of the reel 12 is manually rotated to rewind the cable or rope 15 onto the reel, it will not be possible for the free end 15^a to at any time be brought or 100 caught in engagement between the flange 12^b and the reel supporting frame or hanger 10, as the segmental portions 13^a and cross bar 13^e protect the flanges 12^b and prevent the passage of the cable end 15^a into wedge. 105 contact with the flange reel and its support.

I claim:

1. The combination with a hanger support having inwardly bent terminals, of a reel comprising a central portion with flanged 110

ends and rotatably supported on said terminals, and a guard for said reel, said guard comprising a pair of arcuate end members, said arcuate end members lying in the plane 5 of said reel flanged ends and being supported thereon, cross members connecting said end members, and means connected with said arcuate members for retaining said guard in said hanger support.

10 2. The combination of a support having inwardly bent terminals, a reel rotatably mounted on said terminals, said reel having flanged ends and grooves in the periphery of said flanges, a guard for said reel comprising 15 arcuate end members adapted to lie in said grooves, cross members connecting said arcuate end members, and means for retaining said guard in said support.

3. The combination of a hanger having a 20 plurality of reel supports, a plurality of reels each comprising a central portion with flanged ends rotatably mounted on said supports, a guard for each of said reels comprising arcuate end members, said arcuate end members lying in the plane of said reel flanged ends and being supported thereon, a 25 plurality of cross members connecting said arcuate end members, and means for retaining said guards in said hanger.

30 4. The combination of a hanger having a plurality of reel supports, a plurality of reels rotatably mounted on said supports, said reels having flanged ends and grooves in the periphery of said flanges, a guard for

each of said reels comprising arcuate end 35 members adapted to lie in said grooves and a plurality of cross members connecting said arcuate end members, and retaining means for retaining said guards in said hanger.

5. The combination of a hanger having a 40 pair inwardly bent terminals and hanging means therefor, a pair of extensions intermediate said terminals and said hanging means, a reel rotatably mounted on said terminals, a second reel rotatably mounted on 45 said extensions, said reels having flanged ends and grooves in the periphery of said flanges, a guard for each of said reels comprising arcuate end members adapted to lie in said grooves and a plurality of cross members 50 connecting said arcuate end members, and retaining means for retaining said guards in said hanger.

6. A device as embodied in claim 9, and including said retaining means with openings therein through which said hanger extends whereby said retaining means are adapted for vertical movement in said hanger to permit the removal of the reels. 55

7. A device as embodied in claim 10, and including said retaining means with openings therein through which said hanger extends whereby said retaining means are adapted for vertical movement in said hanger to permit the removal of the reels. 60 65

In witness whereof I affix my signature.

ANTON J. PLOTZ.
